UNITED STATES PATENT OFFICE.

SIEBREN G. DE VRIES, OF GRAND RAPIDS, MICHIGAN.

WATCH AND CLOCK.

Application filed October 14, 1921. Serial No. 507,667.

To all whom it may concern:

Be it known that I, SIEBREN G. DE VRIES, a citizen of the United States, residing at Grand Rapids, county of Kent, State of Michigan, have invented certain new and useful Improvements in Watches and Clocks, of which the following is a specification.

This invention relates to improvements in clocks and watches.

10 The main object of this invention is to provide an improved double-faced clock or watch which is compact and simple in structure.

15 Further objects, and objects relating to details and economies of construction and operation will definitely appear from the detailed description to follow.

20 I accomplish the objects of my invention by the devices and means described in the following specification. The invention is clearly defined and pointed out in the claims.

25 A structure which is a preferred embodiment of my invention is clearly illustrated in the accompanying drawing forming a part of this specification, in which:

Fig. I is a front perspective view of a clock embodying the features of my invention.

30 Fig. II is a detail view of the mechanism frame with part of the gearing, showing details of driving means for the second set of hands.

35 Fig. III is a detail view partially in section on a line corresponding to line 3—3 of Figs. II and IV.

Fig. IV is a detail view partially in section on a line corresponding to line 4—4 of Figs. II, III and V.

40 Fig. V is a detail view partially in section on a line corresponding to line 5—5 of Figs. II and IV.

45 In the drawing the sectional views are taken looking in the direction of the little arrows at the ends of the section lines and similar numerals of reference refer to similar parts throughout the several views.

50 Referring to the drawing, the casing 1 has glass panels, the clock casing 2 being mounted therein. Only one face of the clock casing is shown as the other is a duplicate thereof. The pendulum 3 depends from the casing 2, the trains of gears and the springs being enclosed within the casing 2.

55 The clock is provided with two faces 4. The gearing and springs are supported by a frame comprising spaced side members 5

suitably connected and carried by the shafts and spindles for the trains of gears.

The springs and hand supports are not illustrated as they form no part of this invention and no part of the striking mechanism is shown.

6 designates the main shaft or arbor which is extended through both faces 4. The minute hand 7 at one side is mounted on 65 this arbor 6 to rotate therewith. The hour hand 8 is mounted on the hub 9 of the driven pinion 10. This driven pinion 10 is connected by the train of reducing gears 11 to the pinion 12 on the arbor or shaft 6. 70 This is a common construction.

On the opposite end of the shaft or arbor 6 is a sleeve or cannon pinion 13 having frictional engagement with the arbor. This sleeve or cannon pinion 13 is of well known 75

construction, the sleeve engaging the arbor 6 with sufficient friction to cause the parts to normally rotate together, at the same time permitting relative adjustment as in setting the hands. On the sleeve of this 80

pinion 13 is a sleeve 14 of the sleeve pinion 16. The minute hand 15 is carried by the sleeve 14. The pinion 16 is connected to the shaft 6 through the pinion 13 and the pinions 17 and 18 so that the sleeve 14 is driven at 85

the same speed as the shaft but in the opposite direction. The hour hand 19 is mounted on the sleeve 20 of the sleeve pinions 21 which are connected by a train of gears 22, 23, and 24 to the pinion 16, the 90

pinion 24 being secured to the pinion 16. The sleeve 20 is mounted on the sleeve 14. The hour hand is thus properly timed and driven. This enables the setting of the hands on the reverse side with the main set. 95

With this simple arrangement I provide a double-faced or double dial clock or time-piece with little addition to the regular mechanism. I have illustrated and described my improvement as embodied in one type 100 of clock. I have not deemed it necessary to illustrate other embodiments as I believe the disclosure made will enable those skilled in the art to which my invention relates to embody or adapt the same as may be 105 desired.

Having thus described my invention what I claim as new and desire to secure by Letters Patent is:

1. In a double-faced clock, the combination of oppositely facing dials, a main shaft or arbor, driving means therefor, a minute 110

hand mounted on one end of said arbor to rotate therewith, an hour hand provided with a sleeve rotatably mounted at such end, a train of driving gears connecting said sleeve to said arbor, a driving gear mounted on and having frictional engagement with the opposite end of said arbor, a minute hand sleeve rotatably mounted on said arbor and provided with a gear disposed adjacent to said fixed gear thereon, a minute hand mounted on said sleeve, driving connections for said fixed gear to said gear on said minute hand sleeve, whereby the said sleeve is driven at the same speed as said arbor but in an opposite direction, an hour hand gear provided with a sleeve mounted upon said minute hand sleeve, and a reducing train of gears connecting said minute hand gear with said hour hand gear, all 10 15 20 coaxing for the purpose specified.

2. In a structure of the class described, the combination of a pair of oppositely facing dials, a driven arbor, hour and minute hands coaxing with one of the said dials, driving connections therefor to said arbor, a second minute hand and a second hour hand operatively associated with the other dial and rotatably mounted upon the other end of said arbor, and means, including a gear mounted on and having frictional engagement with said arbor, for driving said second hour and minute hands from said arbor but in a reverse direction, as specified.

In witness whereof, I have hereunto set my hand and seal in the presence of two 35 witnesses.

SIEBREN G. DE VRIES. [L.S.]

Witnesses:

HENRY TER MOLENS,
CORNELIUS VAN DER HEIDE.
